UNITED STATES PATENT OFFICE.

JAMES A. McNULTY, OF KANSAS CITY, MISSOURI.

NAILLESS GRAIN-DOOR FOR RAILWAY-CARS.

1,143,219.

Specification of Letters Patent. Patented June 15, 1915.

Application filed October 10, 1914. Serial No. 865,988.

To all whom it may concern:

Be it known that I, JAMES A. McNULTY, a citizen of the United States, residing at Kansas City, in the county of Jackson and 5 State of Missouri, have invented a certain new and useful Improvement in Nailless Grain-Doors for Railway-Cars, of which the following is a full, clear, concise, and exact description, reference being had to the accompanying drawings, forming a part of 10 this specification.

This invention relates to improvements in nailless grain doors for railway cars.

Hitherto, in shipping grains in box cars, it 15 has been the common practice to close the doors of the car to retain the grain in transit by means of boards or planks nailed across the doorways and on the inner sides thereof. This method necessitates considerable time 20 and labor for applying the boards or planks, and when the cars are unloaded, it is necessary to chop out the boards at one of the doors, thus destroying the wood used for closing the door, losing a certain portion of 25 the grain while chopping the boards, and requiring an unnecessary amount of time and labor. Another disadvantage of the above described means for retaining the grain is due to the fact that the boards 30 forming the closure bulge unevenly during transit because of the great pressure exerted thereon from the inside of the car by the grain. This causes one plank or board to bulge more than the next board or plank adjacent, and permits grain to leak through the 35 gaps or openings thus formed. It has furthermore been found that in chopping off the boards as above described, many of the nails or spikes are left on the insides of the 40 car in the door posts, with the result that when the cars are filled with sacked material such as, flour, the sacks are torn by the spikes or nails with the resultant waste of the sacked material. Also, the continual 45 nailing of the planks to the insides of the door posts, and the chopping away of the planks, soon injures the door posts to such an extent that the same have to be replaced, thus again adding to the necessary expense 50 and loss of income due to the cars being out of service while being repaired.

I am also aware that there are a few grain doors which are permanently applied to cars and are adapted to be moved up under the roof or elsewhere out of position when 55 not required, but such doors are invariably so expensive as to be prohibitive; they add greatly to the dead weight of the cars, and are generally so complicated as to soon get out of service.

The object of my invention is to provide a grain door for railway cars which overcomes all of the above indicated defects and objections; which may be re-used indefinitely; which is adjustable to all standard 60 sized doorways of cars now in service; which is provided with a relief door; which may be applied and taken off in a small fraction of the time now required to apply and remove the boards and planks commonly used; and 65 which is provided with hooks for firmly drawing the doors against the door posts.

The invention furthermore consists in the improvements in the parts and devices and in the novel combinations of the parts and 70 devices herein shown, described or claimed.

In the drawing forming a part of this specification, I have shown one form of my invention, and in said drawing Figure 1 is a side elevation of an entire grain door 75 showing the sections composing the same applied one on top of the other; Fig. 2 is a horizontal sectional view of a portion of a side of a car showing the door opening therein and my improved grain door applied thereto, the section being approximately on the line 2-2 of Fig. 1; Fig. 3 is an enlarged vertical sectional view showing more particularly one of the adjustable hooks, and taken on the line 3-3 of Fig. 1; Fig. 4 is 80 a detail elevational view, upon an enlarged scale, of one of the adjustable hooks; and Fig. 5 is a detail enlarged view showing the 85 form of the free end of the hook.

In said drawing, the grain door is shown 90 as comprised of three sections, A, B and C, the section A being provided with a relief door D. As shown, each section A, B and C is composed of two or more horizontally extending boards 10-10 having ship-lapped joints 11 and, firmly secured together by battens 12 on the rear thereof, and cleats 13 95 100

on the front. The edges of the door sections which are adapted to be brought together are also ship-lapped, as indicated at 14, the object of the ship-lapped joints being to provide a grain-tight joint, and one which will prevent any section bulging more than the adjacent section, thus preventing leakage during transit. Each of the sections A, B and C, at one end thereof, is provided with a hook 15 having an eye 16 at its inner end whereby it is pivotally connected with a screw-eye 17, the hooks 15 being each attached to the door sections A, B and C within a notch 18 formed in the adjacent cleat 13 for a purpose hereinafter specified. On the opposite end of each of the sections A, B and C is provided an adjustable hook 19 which is provided with an eye 20 at its inner end pivotally connected to another eye 21 having an extension 22 which passes through an elongated slot 23 in a plate 24, which plate 24 is secured to the sections A, B and C along the joints thereof, this being done in order to facilitate rabbeting the boards at their joined edges. On the inner side of each plate 24 each eye extension 22 is provided with a washer 25 held in place by a pin or cotter 26, and, as clearly appears from Fig. 3, each eye 21 is provided with an end 27 which, when the eye 21 is aligned with the slot 23, permits the eye to slide back and forth in said slot, but when the eye 21 is turned at right angles or cross-wise of the slot 23, the end 27 cams or forces the eye outwardly and locks said eye in the slot in any of its adjusted positions. Each hook 15 and 19, at its outer end, has a right angled extension 28, the inner face of which is beveled or inclined as indicated at 29, it being understood that the incline or bevel face 29 is on the side nearest the door when the hook is driven into the door posts 30 of the car,—see Fig. 2.

The relief door D, as shown, comprises preferably a sheet of metal slidable in ways or guides 31 formed on the underside of two cleats 32, the door D being held either in closed or open position by means of a pin 33 attached by a chain 34, it being understood that the relief door D may be sealed by the ordinary lead seal when the pin 32 is applied as shown in Fig. 1.

In applying the doors, the section A is first placed on the inside of the car in the position most clearly indicated in Fig. 2, in which it will be noted that the cleat 13 on the left-hand end of the door is up against the left-hand door post 30, thus preventing the door section from sliding longitudinally.

The hook 15 is then driven into the door post by means of a hammer or other suitable instrument, and in so doing it will be apparent that the inclined or bevel face 29 will draw the door section tightly against

the door post 30 as the hook is driven home. On the opposite end of the door section A the hook 19 is adjusted to the proper position, either to that shown in full lines in Fig. 2, or to that shown in dotted lines in the same figure, and corresponding to the width of the doorway, whereupon said hook is driven home in the same manner as previously described for the hook 15. The other door sections B and C are then applied in a similar manner, after which the car may be filled with the grain.

In unloading the cars, the relief door D is first opened, thus permitting the grain to come out through the opening, and as the grain empties out of the car the sections C, B and A may be removed, the hooks being unlatched by merely inserting a hammer or other suitable instrument behind the same to pry them out of the door posts. The cleats 13, while strengthening the door sections as previously described, also serve another function, and that is to protect the hooks 15 and 19 when the door sections are piled one on top of the other.

From the preceding description it will be seen that the door which I have herein shown and described fulfills all the objects hereinbefore set forth, and in actual practice I have found that my improved grain doors may be installed in one-fourth the time required in the operation of nailing and spiking the common board grain doors heretofore generally in use; and the shorter time required for applying and taking off the grain doors not only greatly increases the loading and unloading capacity of the grain elevators where the cars are run to, but also makes possible a quicker return of the equipment to the carrier.

I claim:

1. A grain car door closure including door sections or panels, having their longitudinal edges resting one upon the other and adapted to extend beyond the door casing, hooks arranged on opposite ends of the sections, those on one end being adjustable longitudinally of the panel, said hooks being adapted to be driven into said casings.

2. A grain car door closure including door sections or panels, having their longitudinal edges resting one upon the other and adapted to extend beyond the door casing, hooks arranged on opposite ends of the sections, those on one end being adjustable longitudinally of the panel, said hooks being adapted to directly engage said casings, and means for clamping the hooks at one end in adjusted position.

3. A grain car door closure including door sections or panels having their longitudinal edges resting one upon the other and adapted to extend beyond the door casing, and tension hooks for securing the sections or

panels in place and for forcing said sections or panels laterally into contact with said casing, said hook having ends extending at an angle to their shanks, the inner 5 faces of said ends being inclined outwardly, whereby the sections or panels will be forced laterally into contact with the cas-

ing when said hooks are driven into the casing.

JAMES A. McNULTY.
